[57] CLAIM

The ornamental design for a combined eyedrop dispenser and cover, as shown and described.

DESCRIPTION

FIG. 1 is a top plan view of a combined eyedrop dispenser and cover showing my new design;

FIG. 2 is a side elevational view thereof;

FIG. 3 is an end elevational view thereof;

FIG. 4 is a bottom plan view thereof;

FIG. 5 is a top plan view thereof wherein the cover is removed;

FIG. 6 is a side elevational view thereof;

FIG. 7 is an end elevational view thereof;

FIG. 8 is a bottom plan view thereof;

FIG. 9 is a top plan view of a second embodiment of my design;

FIG. 10 is a side elevational view thereof;

FIG. 11 is a side elevational view thereof wherein the cover is removed;

FIG. 12 is an end elevational view thereof;

FIG. 13 is a bottom plan view thereof;

FIG. 14 is a side elevational view of a third embodiment of my design wherein the undisclosed views are identical in appearance to those of the second embodiment;

FIG. 15 is a top plan view of a fourth embodiment of my design wherein the cover is removed;

FIG. 16 is a side elevational view thereof;

FIG. 17 is a side elevational view thereof wherein the cover is removed;

FIG. 18 is an end elevational view thereof;

FIG. 19 is a bottom plan view thereof;

FIG. 20 is a side elevational view of a fifth embodiment of my new design;

FIG. 21 is a side elevational view thereof wherein the cover is removed;

FIG. 22 is an end elevational view thereof;

FIG. 23 is a bottom plan view thereof.

The top plan view of the fourth and fifth embodiments wherein the cover is attached is identical in appearance to that of the second embodiment.
